Primary Examiner — Susan Moon Lee(74) *Attorney, Agent, or Firm* — Eckert Seamans Cherin & Mellot, LLC(57) **CLAIM**

The ornamental design for an animal groomer, as shown and described.

DESCRIPTION

FIG. 1 is an upper right perspective view of an animal groomer showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a side perspective view thereof; and

FIG. 7 is a side perspective view thereof from the opposite side of FIG. 6; and,

FIG. 8 is a bottom perspective view thereof as squeezed. The environmental broken line showing of a hand in FIG. 8 aids in depicting the Animal Groomer in use, and forms no part of the claimed design.
